(57) **CLAIM**

The ornamental design for a bronchoscope, as shown and described.

DESCRIPTION

FIG. 1 is a perspective view of a bronchoscope according to the present invention.

FIG. 2 is a left side view of the bronchoscope of FIG. 1.

FIG. 3 is a right side view of the bronchoscope of FIG. 1.

FIG. 4 is a rear view of the bronchoscope of FIG. 1.

FIG. 5 is front view of the bronchoscope of FIG. 1.

FIG. 6 is a top view of the bronchoscope of FIG. 1.

FIG. 7 is a bottom view of the bronchoscope of FIG. 1; and, FIG. 8 is an exploded perspective view of the bronchoscope of FIG. 1.

The dashed lines illustrate environment that does not form a part of the present invention, and no claim is made to the material illustrated with dashed lines.
